U.S. Appl. No. 29/639,296, filed Mar. 5, 2018, Curtis Alan Roys.

Primary Examiner — Mark A Goodwin*Assistant Examiner* — Benjamin M Weeks(74) *Attorney, Agent, or Firm* — Scheinberg & Associates, PC; Michael O. Scheinberg**(57) CLAIM**

We claim the ornamental design for a LED mounting adapter, as shown and described.

DESCRIPTION

FIG. 1 is an isometric view of an LED mounting adapter showing my new design;

FIG. 2 is a front elevation thereof;

FIG. 3 is a rear elevation thereof;

FIG. 4 is a left side elevation thereof;

FIG. 5 is a right side elevation thereof;

FIG. 6 is a top plan view thereof;

FIG. 7 is a bottom plan view thereof; and,

FIG. 8 shows the LED mounting adapter in the environment in which it is used.

Broken lines illustrate the environmental structure in the drawing and are not part of the design sought to be patented.
